H. TSCHUDY

DRAWING FRAME FOR SPINNING MACHINES

Filed March 30, 1925

Patented Oct. 27, 1925.

1,559,383

UNITED STATES PATENT OFFICE.

HENRY TSCHUDY, OF ENNENDA, SWITZERLAND, ASSIGNOR TO TSCHUDY SPINNING CORPORATION OF NEW YORK, N. Y., A CORPORATION OF NEW YORK.

DRAWING FRAME FOR SPINNING MACHINES.

Application filed March 30, 1925. Serial No. 19,195.

To all whom it may concern:

Be it known that I, HENRY TSCHUDY, a citizen of Switzerland, residing at Ennenda, Canton Glarus, Switzerland, have invented 5 certain new and useful Improvements in Drawing Frames for Spinning Machines, of which the following is a specification.

This invention relates to improvements in spinning machines, and has particular 10 reference to a drawing frame of the type disclosed in my previous Patent No. 1,469,548, dated October 2, 1923.

In machines such as shown in said patent 15 it has been customary to incline the drawing frame relative to a horizontal plane so as to eliminate in so far as possible, decided or sharp angles in the yarn as it is being drawn through the machine and onto the spindle.

20 By so tilting the frame the bearings for the leather top rolls and the heavy pressure rolls which engage said top rolls, which bearings are perpendicular to the plane of the drawing frame, are inclined forwardly 25 so that practically the entire wear upon said bearings by engagement of the shafts of the rolls therewith is borne by the forward portions of said bearings. Furthermore, it has been found, owing to this wear, 30 that undue friction occurs both upon the bearings and the shafts of the rolls which interferes with the proper operation of the rolls and necessitates more or less frequent replacements.

35 According to the present invention the bearings for the various rolls are so arranged with respect to the plane of the drawing frame as to reduce to a minimum the wear and friction upon said bearings 40 and the shafts of the rolls mounted therein, thus increasing the operating efficiency of the machine and prolonging the utility of the parts.

The inventive idea involved is capable of 45 receiving a variety of mechanical expressions one of which, for the purpose of illustration, is shown in the accompanying drawing; but it is to be expressly understood that said drawing is used merely to facilitate the description of the invention as a 50 whole and not to define the limits thereof, reference being had to the appended claims for this purpose.

55 In the drawing—

Figure 1 is a vertical longitudinal sec-

tion through the spinning machine substantially on the line 1—1 of Figure 2;

Figure 2 is a fragmentary front elevation;

Figure 3 is a section taken on the line 60 3—3 of Figure 4; and

Figure 4 is a perspective view of one of the bearing members employed in connection with the invention.

As shown in the drawing the machine 65 includes a standard 5 upon which the drawing frame is mounted, said frame consisting of upper and lower sections 6 and 7 arranged in a forwardly and downwardly inclined position. This disposition of the drawing frame is made for the purpose of eliminating from the yarn, as it passes from the bobbin through the drawing frame to the spindle, decided or sharp angles there- 70 in so that the yarn will be in substantial 75 alignment with the inclination of the frame. The upper section 7 of the frame may be adjustable relative to the lower section and secured in various adjusted positions by means of the bolt 8. The sections 6 and 7 support the usual fluted lower front, 80 intermediate and rear drawing rolls 9, 10 and 11, respectively, the shafts of which are disposed in the customary bearings. A lower front clearer roll 12 is also supported by the frame in engagement with the front roll 9 and is provided with the customary 85 felt cover 13 which operates to remove the "fly" from the roll 9. A similar clearer roll 14 of a larger size than the roll 12 is 90 supported by a member 15 in engagement with the intermediate and rear drawing rolls 10 and 11.

A bearing member, generally indicated 95 by the numeral 16, is mounted at its rear end for pivotal movement upon a shaft 17 so that said member may be adjusted relative to the drawing frame and a set screw is utilized for securing said member in position. The rear portion of the bearing 100 member 16 is arranged in a substantially horizontal plane while the forward portion is downwardly inclined so as to be in substantial parallel relation to the upper surface of the drawing frame when said member 105 is resting thereon. The intermediate portion 19 of the bearing member is provided with a vertically disposed support 20 for a purpose which will presently appear. Forwardly of the portion 19 the member 110

16 has a bearing 21 which is formed by cutting away the member to provide oppositely disposed recesses 22, the sides of which are vertically arranged when the member 16 is in its inclined and operative position. The member 16 further includes a second front bearing 23 formed in a manner similar to the bearing 21 and provided with a rearwardly projecting extension 24 mounted in a suitable groove 25 formed in the bottom of the member 16. This member 24 is slidable in said groove so as to permit of a longitudinal adjustment of the bearing 23. A bolt 26 extended through the portion 19 of the member 16 may be utilized to engage the extension 24 and secure the bearing 23 in its adjusted positions. A pressure roll 27 has the ends of its shaft disposed in the bearings 21 of the member 16 arranged on each side of the drawing frame and likewise the leather covered top rolls 28 have the ends of the shaft thereof disposed in the bearing 23 between the vertical side walls thereof. The vertical disposition of the sides of the bearings 21 and 23 in contradistinction to the inclination of said bearings as shown in the above mentioned patent, permits the shafts of the rolls 27 and 28 to bear with practically equal pressure against the sides of the bearings and thus eliminates the difficulty experienced with the mounting of the shafts in said patent, this difficulty being due to the shafts being practically entirely supported by the front sides of the bearings in which they are mounted, thus occasioning undue wear and friction upon said sides and the shafts. With the present construction this wear and friction is relieved and the rolls 27 and 28 are free to move in a vertical plane relative to the lower drawing rolls 9 and 10.

A rear weighted feeding roll 29 is supported above and in engagement with the rear drawing roll 11 in the customary manner.

The rear portion of the bearing 16 is utilized to support an arm 30, which also rests upon the upper end of the support 20 of the bearing member, said arm being adjustably secured in operative position by means of a bolt 31 extending through a slot 32 in the arm and projecting into an opening 33 in the bearing member. The forward end of the arm is bent to provide a bearing 34 of U shaped formation also having vertical sides and capable of receiving one end of the shaft 35 which supports the large weighted pressure rolls 36. One of the arms 30 is provided upon each side of the set of rolls and the latter are freely sup-

ported in the bearings 34 for vertical movement therein so as to properly contact the top rolls 28 to exert the proper pressure thereon. It will be apparent that by arranging the sides of the bearing 34 in vertical planes the wear and friction which would be occasioned if said sides were inclined is eliminated and only a minimum amount of friction and wear occurs between the bearings 34 and the ends of the shaft 35. 65 70

What is claimed is:

1. In a spinning machine, an inclined drawing frame, bearings supported thereby, top rolls having shafts supported in said 75 bearings for only vertical movement therein, pressure rolls for said top rolls, and bearings having vertical sides for receiving therebetween the ends of said pressure rolls.

2. In a spinning machine, a forwardly 80 and downwardly inclined drawing frame, a bearing member supported upon said frame in an inclined position and including a plurality of bearings, the sides of which are arranged in vertical planes, rolls 85 having their shafts disposed between and engaging the opposed sides of said bearings and capable of only vertical movement therein, an arm supported above said bearing member and including a bearing having 90 vertical sides, and a pressure roll having its shaft mounted between the sides of said bearing for vertical movement therein.

3. In a spinning machine, a forwardly and downwardly inclined drawing frame, a 95 bearing member supported upon said frame in an inclined position and recessed on opposite sides to provide a plurality of bearings, the sides of which extend the depth of said member and are arranged in vertical 100 planes, and rolls having their shafts disposed between and engaging the opposed sides of said bearings and capable of only vertical movement therein.

4. In a spinning machine, a forwardly 105 and downwardly inclined drawing frame, a bearing member supported upon said frame in an inclined position and recessed on opposite sides to provide a plurality of bearings, the sides of which extend the depth 110 of said member and are arranged in vertical planes, one of said bearings having an extension slidable longitudinally of said member to adjust said bearing relative to the other bearing, means to secure said extension in adjusted position, and rolls having their shafts disposed between and engaging the opposed sides of said bearings and capable of only vertical movement therein. 115

In testimony whereof I have affixed my 120 signature.

HENRY TSCHUDY.
